(Cl. D31—4)

FIG. 1

FIG. 4

FIG. 2

FIG. 3

FIG. 5

FIG. 6

FIGURE 1 is a front perspective view of a fishing lure embodying my new design;

FIGURE 2 is an enlarged top plan view thereof;

FIGURE 3 is a right side elevational view thereof, as shown in FIGURE 2;

FIGURE 4 is a left side elevational view thereof as shown in FIGURE 2, but with the spinner, beads, and hook omitted for convenience of illustration;

FIGURE 5 is a rear elevational view thereof as shown in FIG. 4; and

FIGURE 6 is a front elevational view thereof as shown in FIGURE 4.

The dominant features of my design reside in the full line portions of the drawing.

I claim:

The ornamental design for a fishing lure, as shown and described.
